MILL HAMMER WITH REMOVABLE TIP

Charles Le Blanc, Montreal, Quebec, Canada

Application March 29, 1951, Serial No. 218,120

5 Claims. (Cl. 241—197)

1

The present invention relates to hammer mills and more particularly to a mill hammer with a removable working tip.

Hammer mills used for crushing stones and ores such as in the manufacture of cement, generally consist in a horizontal or vertical shaft, rotating at high speed, on which is mounted, either rigidly or pivotally, one or more crushing elements which may consist of hammers or the like.

Such hammers, although made of a material highly resistant to shock, wear out very rapidly due to the considerable abuse to which they are subjected, consequently they have to be replaced rather frequently and therefore constitute a major item in the operating expenses of the mill.

Moreover, because such hammers are relatively heavy and have a substantial volume, the housing of the hammer mills have to be partly dismantled for removing such hammers thereby prolonging unduly the stoppage of the mill.

According, the general object of the present invention is the provision in hammer mills of a hammer with a removable tip which will effect a considerable saving in the operation of the mill.

A very important object of the present invention is the provision of a mill hammer made in two separate parts, the main part of which will give a considerably prolonged service.

Still another important object of the present invention is the provision of a mill hammer having a removable tip which provides the shock absorbing surface of the hammer, said tip being readily removed and replaced without having to dismantle the mill housing and to dismount the whole hammer from the mill.

Yet another important object of the present invention is the provision of a mill hammer having a removable tip wherein the fastening means between the tip and the body of the hammer are of novel and improved construction effecting a very secure attachment which will not be affected by the impacts or shocks received by the hammer.

The foregoing and other important objects of the present invention will become more apparent during the following disclosure and by referring to the drawings in which:

Figure 1 is a cross-sectional elevation of a hammer mill with hammers according to the invention;

Figure 2 is an enlarged elevation of the hammer according to the invention;

2

Figure 3 is a cross-section along line 3—3 of Figure 2;

Figure 4 is a section along line 4—4 of Figure 3;

Figure 5 is a cross-section along line 5—5 of Figure 2; and

Figure 6 is an end view partly in section along line 6—6 of Fig. 2.

Referring now more particularly to the drawings in which like reference characters indicate like elements throughout, Figure 1 represents one type of hammer mill in which may be used the hammers, according to the invention. Said hammer mill comprises a horizontal shaft 1 rotating at high speed, on which is keyed a drum or disc 2 bearing equally spaced stub shafts 3 pivotally mounting the swinging hammers generally indicated at 4, said hammers being of the improved construction according to the invention.

The bottom of the mill housing is provided with a cylindrical screen placed under the hammers and preferably constituted by a plurality of grate bars 5, the spacing of which may or may not be adjustable, to let through crushed particles of the desired size or mesh.

The ore is fed into the mill through a suitable aperture 6 and is crushed by the working face of the rotating swinging hammers 4 until it passes between the grate bars 5.

The hammer 4, according to the invention, comprises an eye 7 for loosely receiving the stub shaft 3, said eye 7 being connected to the main body 8 through the intermediate of a neck 9.

The main body 8 and the removable tip 10, when fastened together, have a more or less rectangular overall shape except for the outer side working face 11 of the tip 10, which flares slightly outwardly from the neck 9, and the outer side face 12 of the body 8, which is bevelled at 13.

Furthermore, the hammer 4 has preferably a rectangular cross-section as shown in Figure 5.

The removable tip 10, according to the invention, has a substantially triangular shape and its inner side face adapted to contact the body 8 has a step-like formation defining two tongues and grooves 14 and 15 respectively, extending transversely of said face and adapted to engage and receive respectively similar co-operating grooves and tongues made in the contact face of the body 8. The tongues 14 extend from root to tip longitudinally of the contacting faces and outwardly

from the eye 7, whereby the centrifugally developed outward radial thrust of the tip 10 will be transferred to the body 8. The general line of separation of the body 8 and of the removable tip 10 will be substantially inclined relatively to the

longitudinal axis of the hammer according to the invention so that the thrust or shock received by the tip 10 will be absorbed to a substantial degree by these tongue and groove attachments. To further reinforce the fastening of the tip to the body, said body is provided with a longitudinally extending dovetail projection 16 made at the contact face of the body intermediate the two groove and tongue attachments. The dovetail projection 16 will engage a correspondingly shaped recess 17 made at the contact face of the removable tip 10.

The upper small end of the tip 10 is provided with a recess 18 aligned with a bore 19 made in the neck 9 of the main body 8, said bore opening 15 at its other end into the recess 20 made in the neck 9 and part of the eye 7 of the hammer. The longitudinal axis of the bore 19 extends preferably at an angle relatively to the longitudinal axis of the hammer and at right angles to the contacting faces of the body 1 and removable tip 10.

A wedge bolt 21 is inserted through the bore 19 with its larger end 22 abutting against the curved bottom 23 of the recess 18 of the tip 10 and having its other end threaded to receive the nut 24 which is preferably a stop nut such as manufactured by the Elastic Stop Nut Corporation of America under the trade name of "Esna," said nut housing a fiber washer frictionally engaging the threads of the bolt 21.

Upon tightening the nut 24, the head 22 of the bolt 21 will press down against the tip 10 and thereby will urge engagement of the co-operating tongues and grooves 14 and 15 at the contacting faces of the removable tip 10 and body 8. It will 35 be noted that the nut 24 is substantially completely enclosed in the recess 20 thereby preventing injury to the same.

In order to allow free engagement of the wedge bolt 21 into the bore 19 the latter is provided with a longitudinal recess 25 extending at the bottom of said bore 19 from the contacting face of the body 8 to approximately the middle portion of said bore and with a second top recess 26 extending from the recess 20 downwardly past the middle portion of said bore 19.

The side edges of the working face 11 of the tip 10 are preferably rabbeted as shown at 27 to prevent chipping of said tip 10. Similarly the lower inner corner of the tip 10 at the contacting face of the same is preferably bevelled as shown at 28 together with the lower corner 29 of the outside face 12 of the main body 8. The outer large end face 30 of the working tip 10 forms the base of said triangular tip and is substantially flush with the outer end face 31 of the body 8.

In practical experiments with the hammer, according to the invention, the removable tip 10 has been replaced at least twenty times without having to change the main body of said hammer, thereby increasing the life of said body twenty times relatively to a conventional mill hammer.

Furthermore, it has been found that the attachment described hereabove is very secure, no breakdown of the bolt 21 having ever occurred.

An advantage, according to the invention, is that the removable tip 10 may be easily replaced without having to dismantle the housing of the hammer mill. Therefore, the time of stoppage of the hammer mill is reduced to a minimum.

While a preferred embodiment according to the invention has been illustrated and described it is understood that various modifications may be resorted to without departing from the spirit and scope of the appended claims.

I claim:

1. A mill hammer of the swinging type comprising a main body adapted to be supported at its inner end, integral fastening means formed on a side face of said body, a removable working tip for said hammer of substantially triangular shape, integral complementary fastening means formed on one of the side faces of said removable tip to removably interlock with the fastening means on said side face of said body, a bolt extending through said tip and said body to prevent disengagement of said interlocking fastening means, the contacting faces of said main body and said removable tip extending at an angle relatively to the longitudinal axis of said hammer and at an angle relatively to said bolt, the outer end face of said working tip forming the base of said triangular tip and being substantially flush with the outer end face of said body.

2. A mill hammer of the swinging type, comprising an elongated main body, an eye rigidly dependent from said main body at one end, integral fastening means formed on a face of said body, said face extending at an angle relatively to the longitudinal axis of said body, a removable working tip for said hammer of substantially triangular shape, integral complementary fastening means formed on one side face of said removable tip to removably interlock with the fastening means of said body, a wedge bolt extending through said tip and said body adjacent said eye to urge engagement of said interlocking fastening means, said working tip being bevelled at its corner adjacent to the contacting face of said main body and away from said eye.

3. A mill hammer of the swinging type comprising an elongated main body, an eye rigidly dependent from one end of said main body, said body having a contacting face extending at an angle relatively to the longitudinal axis of the same, a triangular shaped removable working tip for said hammer, having a side face adapted to contact the contacting face of said body, the contacting faces of said main body and of said working tip having a step-like formation defining interlocking tongues and grooves extending transversely of said contacting faces, said contacting faces further provided with a dovetailed projection and corresponding recess extending longitudinally thereof between said transverse tongues and grooves, and a wedge bolt extending through said tip and said body to urge engagement of said tongues and grooves.

4. A mill hammer of the swinging type comprising a main elongated body adapted to be supported at one end, integral fastening means formed on a face of said body, said face extending at an angle relatively to the longitudinal axis of said body, a removable working tip for said hammer of substantially triangular shape, integral complementary fastening means formed on one side face of said removable tip to removably interlock with the fastening means of said body, and a bolt extending through the small end of said tip and said body adjacent said supported end to maintain engagement of said interlocking fastening means.

5. A mill hammer comprising a main body adapted to be supported at its inner end, a removable working tip for said hammer of substantially triangular shape, having a side face contacting one side face of said main body, integral interlocking means including transverse

spaced tongues formed on said side face of said working tip extending from root to tip longitudinally of said side face of said working tip and towards the outer end of the latter, said tongues engageable with complementary transverse grooves formed on the contacting side face of said body and a dovetailed projection and corresponding recess extending longitudinally of said contacting faces between said tongues and grooves, whereby said interlocking means become engaged upon outward longitudinal displacement of said working tip relatively to said body with their contact faces sliding upon each other.
